ATTORNEY

UNITED STATES PATENT OFFICE.

EARL E. BERRY, OF KENNETT SQUARE, PENNSYLVANIA, ASSIGNOR TO AMERICAN ROAD MACHINERY COMPANY, INC., OF KENNETT SQUARE, PENNSYLVANIA, A CORPORATION OF DELAWARE.

SHAKER-SCREEN.

1,357,307.

Specification of Letters Patent.

Patented Nov. 2, 1920.

Application filed February 21, 1919. Serial No. 278,453.

To all whom it may concern:

Be it known that I, EARL E. BERRY, a citizen of the United States, residing at Kennett Square, county of Chester, and State of Pennsylvania, have invented a new and useful Improvement in Shaker-Screens, of which the following is a full, clear, and exact description, reference being had to the accompanying drawings, which form a part of this specification.

My invention relates to shaker screens and has for its object to improve the general construction of the screen and improved means for imparting such vibrating movements to the screen as will effect the continuous agitation of the material and prevent material, such as wedge-shaped stones, clinging to the screen sections.

It is known, in shaker screens, to actuate them from connecting rods operated from eccentrics or cranks on a common shaft, and also to secure such rods rigidly to the screen and to provide the rods with reduced sections or otherwise provide for allowing them to flex to allow for the constant change in the angular direction of extension of the rods from the screen. One of the specific objects of my invention is to provide improved means for securing the rods to the screens. The invention also comprises an oscillating knocker to prevent any material clinging to the screen sections and improvements in the general construction.

A preferred embodiment of my invention is shown in the accompanying drawings, in which—

Figure 1 is a general plan view of the screen structure.

Fig. 2 is a general side elevation of the same.

Fig. 3 is an enlarged detail side view of the connecting rod and its connections.

Fig. 4 is an enlarged cross-section on the line 4—4 of Fig. 1.

Fig. 5 is an enlarged detail sectional view on line 5—5 of Fig. 3.

From the transverse wooden cross-beams *a* depend flexible hangers *b* to which are bolted opposite ends of transverse angle bars *c*. Near opposite ends of angle bars *c* longitudinally extending channel bars *d* are secured. These channels form the sides of the screen

proper. The screen sections *e* are bolted to these channels. There are two sets of screens at different levels.

The connecting rods are secured to the screens in the following manner. To each of the channels *d* are bolted an upright gusset plate *g* and an angle *h*, another angle *h'* being bolted to the top of the gusset plate. The plate *g* and angles *h*, *h'*, form a channel in which neatly fits the end of a connecting rod *k*. To the gusset plate is attached a circular steel disk *i* closely fitting a recess in the connecting rod. Bolts *j* draw the rod *k* to the plate *g*, one of the bolts extending through the disk *i*. The disk *i* acts as a thrust bearing. When the bolts are drawn up for attaching the gusset plate to the connecting rod, the described construction gives a tight fit, eliminating the load from the bolts and avoiding the possibility of the parts coming loose.

Each connecting rod *k* is of wood and is tapered down to a small section in the middle so as to give the necessary flexibility. The end of the rod adjacent the crank shaft is reinforced by top and bottom metal strips *m* and a metal end head *n* bolted to end flanges on the strips *m*. The rod is orificed to receive its corresponding crank on the shaft *o*.

There are four cranks and four corresponding connecting rods. Two of these rods are secured to opposite sides of the lower screen structure. The other two rods actuate the upper screen structure.

Knocker rods *r* extend across beneath each screen adjacent its bottom. Each rod at each end is bent upward and inward and turns in a bearing *s* secured to a channel *d*. The bearing has a removable bushing and is protected from sand and water by being covered with a cap *t*, which in turn carries a grease cup *u* for lubrication. The knocker rod *r* is caused to oscillate back and forth by the reciprocatory motion of the screen itself. The rod, in its swinging movement, hits the bottom of the corresponding screen section, causing a rapid vibration thereof, thereby dislodging from the screen section any wedge-shaped stones or other material which otherwise would cling tightly thereto.

Having now fully described my invention,

what I claim and desire to protect by Letters Patent is:

1. A shaker screen, having a channel structure, a connecting rod extending into said channel structure, the inner side of the connecting rod being recessed, a disk within said recess, and means for clamping the faces of the disk between the channel structure and the bottom of the recess in the connecting rod.

2. A shaker screen, having a channel structure secured thereto, a connecting rod, one of the ends of the connecting rod being bolted between the flanges of the channel structure, the bolt passing through the side of the channel structure and the connecting

rod, there being a recess formed in the connecting rod, a thrust plate for the connecting rod within said recess and engaging the side of the channel structure, and a bolt passing through the connecting rod, thrust plate and the side of the channel structure for securing the parts in position with relation to each other.

In testimony of which invention, I have 25 hereunto set my hand, at Kennett Square, Pa., on this 18th day of February, 1919.

EARL E. BERRY.
